UNITED STATES PATENT OFFICE.

AUGUST OLSON, OF PHILADELPHIA, PENNSYLVANIA, AND LOUIS W. G. FLYNT, OF ROCHESTER, NEW YORK, ASSIGNORS TO QUENTIN W. BOOTH AND IRVING E. BOOTH, OF ROCHESTER, NEW YORK.

SHOE-MACHINE.

No. 826,352.

Specification of Letters Patent.

Patented July 17, 1906.

Application filed August 26, 1904. Serial No. 222,309.

To all whom it may concern:

Be it known that we, AUGUST OLSON, a citizen of the United States, residing at Nineteenth and Buttonwood streets, Philadelphia, county of Philadelphia, and State of Pennsylvania, and LOUIS W. G. FLYNT, a subject of the King of Great Britain, residing at 876 Genesee street, Rochester, in the county of Monroe and State of New York, have invented certain new and useful Improvements in Shoe-Machines, of which the following is a specification, reference being had therein to the accompanying drawings.

This invention relates to shoe machinery, and has for its object the provision of a machine possessing novel characteristics rendering the same practical and highly efficient for various uses—notably, in producing an animation stitch or stitch-impression on the upper exposed surface or edge of the soles of boots or shoes or upon the welt thereof.

The invention comprehends the provision in a machine of the type above referred to of a tool in combination with improved means for imparting thereto a differential forward and retrograde movement, also an angularly-adjustable support or table operatively associated with said tool, preferably, though not essentially, yieldably mounted.

The invention further embraces improved adjusting instrumentalities for the tool-actuating means and means whereby the support or table may be shifted away from the tool to permit the insertion of the work therebetween.

The invention still further comprehends means for successively regulating the tool-actuating means and the shifting of the table or support.

Among the novel features of a machine constituting a preferred embodiment of the invention are included a guard associated with an impression-tool, a brake for said tool, and a clutch-device interposed between the driving power and the main shaft of the machine, as well as many improved details in the construction and arrangement of the several parts of the machine, all of which will be apparent from the description herein-after when read in connection with the accompanying drawings, forming part hereof, and wherein a convenient embodiment of the invention is illustrated.

In the drawings, Figure 1 is a perspective view of the complete machine. Fig. 2 is a vertical longitudinal sectional view, parts being shown in elevation and other portions broken away. Fig. 3 is a vertical transverse sectional view on the line $z z$ of Fig. 2. Fig. 4 is a view similar to Fig. 3 on the line $y y$ of Fig. 2, looking in the direction of the arrow. Fig. 5 is a plan view of the impression-tool and its immediately-associated parts. Fig. 6 is a vertical longitudinal sectional view on the line $z z$ of Fig. 5; and Fig. 7 is a detail perspective view, parts being broken away, of the impression-tool and its guard.

Referring now more specifically to the drawings, wherein like reference characters refer to corresponding parts in the several views, A designates a frame, which in the main constitutes a hollow support for the operating mechanism and serves also to inclose or house the same, said frame having a suitable base or column. Two rotatable shafts arranged in parallel planes are supported one above the other in the frame A, the same being represented at B and C, respectively, and the former serving as the main drive-shaft and the latter the rotating shaft for an impression-forming tool D, the details of which latter will be hereinafter described.

The shaft B is adapted to be rotated by a pulley E, arranged conveniently at one end thereof and operatively related to any desired source of power. (Not shown.) The opposite or inner end of this shaft is fitted with a crank b and crank-pin b', the latter connecting loosely with a saddle F, mounted to oscillate upon the shaft C. The saddle just mentioned carries two pawls f f', pivotally supported upon cross-pins f², spanning the space between the opposite members of the saddle, Fig. 2, and the pawls are disposed one at each side of the vertical axis of a toothed ratchet-wheel G, keyed or otherwise fastened to the shaft C. These pawls are constantly drawn inwardly toward each other under the tension of a spring g, which connects them, and when otherwise unobstructed they engage the teeth of the ratchet G and through the medium thereof rotate the shaft C alternately in opposite directions, one pawl rotating the shaft in one direction on the downstroke of the pitman,

while the other rotates it in an opposite direction on the upstroke thereof.

The differential or relative extents of movement of the pawls and the means for regulating the same may now be defined.

On the shaft C and free to revolve thereon are sleeved a pair of cams H, the same being provided with outwardly-extending arms h on opposite sides of the shaft, to which are pivoted knuckles i j of treadle-rod I J. The lower ends of the treadle-rod are in turn pivoted to the treadle K at different distances from its pivot k, (clearly indicated at i' j'). Such being the arrangement, it is obvious that a movement of the treadle will revolve the cams H around the shaft C, the one to a greater extent than the other. In practice one treadle-rod, I, is placed about twice the distance from the pivot k of the treadle as the other rod, J, so that one cam, the former, will receive approximately twice the movement of the other. The cams have raised portions h', (best seen in Fig. 4,) which when the cams are rotated under the free ends of the pawls, said pawls having extended portions f³ for this purpose, will raise them out of engagement with the teeth of the ratchet G, and thereby correspondingly limit or stop the rotation of the shaft C, said raised portions being so positioned relative to the pawls that the one pawl engages a greater number of teeth than the other, the resultant movement being a differential forward and retrograde rotation of the shaft C and tool B, the forward movement being always greater, whereby a progressive oscillation of the impression device is maintained.

The treadle K is normally held in its retracted or uppermost position by means of a spring k', fastened at one end thereto and at the opposite end to the base or column of the frame A, and when the treadle is in this position the shaft C receives its greatest movement under the actuation of the pawls. On the other hand, by a depression of the treadle the cams H are rotated upon the shaft, and a less number of teeth are engaged by the pawls in proportion to the movement of the cams, the forward movement being reduced in a greater proportion than the reverse movement, so that the work will continue to be evenly fed although the play of the pawls be greatly reduced. For instance, if the machine be effecting an actuation of the impression-tool five teeth forward and three teeth back when the treadle is in its uppermost position referred to then by simply depressing or adjusting said treadle the extent of actuation may be readily regulated in the proportion of three teeth forward and two teeth backward, it being understood that a full depression of the treadle will shift the parts sufficiently to stop the movement of the impression-wheel.

A screw S, threaded through a lug s on the base or column of the frame A, bears upon the upper edge or surface of the treadle K, thereby limiting the upward movement of said treadle under the influence of the spring k', a lock-nut s' retaining the screw in adjusted position.

The construction of the impression-tool, it being preferably in the nature of a knurling-wheel, will be clear from an inspection of the drawings. The same is of frusto-conical formation, its largest diameter being outermost and the periphery thereof being toothed throughout its extent. The inner end of the wheel is grooved or recessed, as at d, for the reception of a lug or key d' on the end of its shaft C, the parts being locked together by a screw D' passing axially through the wheel D and into the end of its shaft.

Another feature of the invention is the provision of a brake for insuring against rotation of the shaft C when the pawls f f' are disengaged from the teeth of the ratchet-wheel G. This brake includes the following instrumentalities: W represents a spring seated within the inner bearing W' of the frame A for the shaft C and interposed between a washer w, directly abutting the inner end of said shaft, and a headed adjusting-screw w' in line with the shaft. w² is a collar fixed to the shaft C in any desired manner, conveniently by a key w⁴, and w³ is a fiber or other washer arranged between said collar and the end of the outer bearing W² of the frame A for the shaft C. The pressure applied by adjusting the screw w', transmitted through the spring W and washer w to the inner end of the shaft, thrusts the shaft outwardly in a longitudinal direction, and thereby shifts the collar w² to cause the fiber washer w³ to be impinged between the same and the end of the outer shaft-bearing, as before stated, whereby sufficient friction is created between the parts to adequately prevent rotation of the shaft C excepting when forcibly actuated by the pawls. The utilization of the spring W obviates the fine adjustment which would be necessary were the screw w' alone employed.

Operatively related to the impression-tool and conveniently therebeneath is a rotatable support or table L of substantially circular contour and beveled outwardly on its upper surface from its center to its periphery, as at l. The table is arranged at an angle to the axis of the shaft C, although the former approximates a horizontal plane, the relation of the table to the tool D being such that the toothed periphery of the latter and the beveled face of the former may be brought into substantial parallelism. The table is pivotally supported by means of a pin l', depending from the bottom thereof and loosely fitting a recess m in a carrier-block M, said

block in turn being pivoted upon a horizontally-disposed pin m' , passing therethrough and having bearings in separated lugs or ears N of a plunger O to be now described.

5 The plunger O conforms generally to the interior of and is slideable within a casing o , projecting forwardly from the frame A . A coiled spring P , confined within the lower part of the casing o , yieldably supports the 10 plunger, Fig. 2, the upper end of said spring bearing against an annular seat o' at the bottom of the plunger and receiving a centering stem or projection o'' thereof, while the lower end of the spring seats upon a thimble p , which is adjustable through the medium 15 of a screw p' , having a threaded engagement with the bottom of the casing o and locked in adjusted position by a nut p'' . The plunger O is slotted at q to receive the end of a lever Q , which rests upon a pin q' in the plunger and bears at its opposite end upon a flange a in the frame A , this last-mentioned end being confined against lateral movement by vertical pins a' . A table-shifting rod R is pivot- 20 ed to the lever Q at a point intermediate its ends and depending therefrom passes freely through a vertically-disposed aperture r in the treadle K , an adjustable collar or nut engag- 25 ing said end at a point a predetermined distance beneath the under side of the treadle when in its normal or raised position.

The purpose of the nut r' and the free engagement of the rod R with the treadle will be now pointed out.

30 When the treadle is first depressed, it will play over the rod R until its under face strikes the nut r' , when a continued downward movement of said treadle draws said rod in a corresponding direction, thereby lowering the 35 outer end of the lever Q , and consequently through the plunger O lowers the table L for the insertion and removal of the work to be operated upon. Owing to the distance or 40 space between the under side of the treadle K and the nut r' on the rod R sufficient freedom is afforded between the parts, whereby 45 the initial manipulation of the treadle pulls the treadle-rods I and J to at first slow down and subsequently stop the operation of the 50 impression-tool under the action of the cams and pawls hereinabove referred to all prior to the bringing of the rod R into action. However, the adjustment is such that immediately upon the stoppage of the impression- 55 tool the treadle will abut the nut r' and lower the table L , as aforesaid.

As a means for adjusting the angular position of the table L we employ a headed screw T , bearing upon the under surface of the free 60 end of the carrier-block M , in which said table is rotatably supported. The screw enga- 65 ges a threaded recess t in the plunger O , disposed at an inclination approximating that of the axis of the pin l' .

55 To prevent an undue elevation of the table

under the action of the screw T , plunger O , and spring P , some means is necessary to limit the upward movement of the plunger, and to this end we provide a headed screw U , passing loosely through a perforated projection u , extending rearwardly from the plunger O and also through an aligned opening u' in the frame A , the threaded end of the screw carrying a nut u'' , adapted to contact the frame A surrounding the opening u' , as is obvious.

70 Another detail of importance resides in means for relieving the pivot-pin l' of the table L of lateral or sidewise strain, said means comprising a roller V , loosely secured upon the reduced inner end v of the block M , whereby the roller is arranged adjacent to the periphery of the table and bears against the under surface thereof directly beneath the impression-tool, this being the point of 85 greatest operating pressure upon the table.

75 A guard 14 (see Figs. 1 and 7) covers the outer or end face of the impression-tool and serves to prevent the upper from being scratched or marred by being forced against 90 or otherwise coming in contact with the wheel. This guard is composed conveniently of a thin piece of sheet metal U -shaped in cross-section, to the ends of which are secured two ferrules 15 15. These ferrules engage over two pins 16 16, which are secured in the frame A on opposite sides of and parallel with the shaft C .

80 The driving-pulley E is normally loose on the main shaft B and is provided with two bearing-bushes 2 2, preferably of brass or bronze metal, and a hardened-steel bush 3, which is interposed between the bushes 2 2. The bushes 2 2 fit the shaft B , while the bush 3 is bored considerably larger. The rear end 85 of the shaft is drilled longitudinally, as at 4, to receive a clutch-rod 5, and is also drilled laterally, as at 6, to receive a steel ball 7. In the same vertical plane with this ball are one or more holes 8 in the steel bush 3, these 90 holes being somewhat smaller than the diameter of the ball. The inner end 5' of the clutch-rod 5 is substantially conical in shape, and the steel ball rests on its periphery. This conical end of the clutch-rod is of such 95 dimensions that when the ball rests on its smallest diameter the same does not come in contact with the bush 3; but when the rod is pulled out it forces the ball through the hole 6 in the shaft B and against the inner face of 100 the bush 3 until it finds one of the holes in the bush, when it is forced partly in and is held between the bush and the shaft, and as the bushing is secured in the pulley the shaft is gripped and must rotate with the pulley. 105 The outer end of the rod 5 is shouldered at 9 to receive a knob 10, which is loose on the rod and is held in position by a screw 11. This knob constitutes a handle to operate the 110 clutch-rod.

12 is a collar secured to the shaft B by a screw 13 and serves to retain the pulley against movement along the shaft.

5 A cover 17 is fitted to the top of the frame to complete the casing and protect the working parts of the machine.

10 It is to be understood that numerous alterations and changes may be made in the machine herein disclosed without in the least departing from the spirit of the invention.

15 Having thus described the invention, what is claimed as new, and desired to be secured by Letters Patent, is—

1. In a shoe-machine, a tool, means for effecting a forward and retrograde movement of said tool including a ratchet member, pawls adapted to engage said ratchet member, and means for actuating the pawls whereby the movement of the ratchet in one direction is 20 greater than a movement in its reverse direction, and means for adjustably regulating the extents of said forward and retrograde movements comprising shiftable cam mechanism for adjusting the extents of play of the pawls.

25 2. In a shoe-machine, a tool, means for effecting forward and retrograde movements of said tool including instrumentalities whereby the extent of movement in one direction is greater than that in a reverse direction, and means for adjustably regulating said movements.

30 3. In a shoe-machine, a tool, mechanism for effecting forward and retrograde movements of said tool including instrumentalities whereby the extent of movement of the tool in one direction is greater than in a reverse direction, and means for adjustably regulating the extents of said movements while preserving their relative proportional extents of 35 movement.

40 4. In a shoe-machine, a tool, means for effecting differential forward and backward movements thereof, and means for adjustably regulating the extents of said movements while preserving their relative proportional extents of movement, said last-mentioned means comprising a ratchet member, pawls adapted to engage the same, shiftable cams one for each pawl, and means for shifting the cams including a pivoted operating device and a connection between each cam and said operating device engaging the latter at points located at varying distances from the pivot of the operating device.

45 5. In a shoe-machine, a tool, a work-table operatively associated therewith, a carrier-block for pivotally supporting said work-table and in the free end of which the table is rotatably mounted, and means for forcing 50 said block to various positions of adjustment on its pivot comprising an adjustable screw device beneath said carrier-block and substantially in axial alinement with the axis around which the table rotates.

60 6. In a shoe-machine, a rotatable tool, a

shaft therefor, a main drive-shaft, mechanism operatively associated with said main drive-shaft and the tool-shaft whereby the movement of the tool is greater in one direction than in a reverse direction, and means 70 adjustable during the actuation of the main drive-shaft and without interfering with the normal operation thereof for adjusting the extents of movements of the tool.

7. In a shoe-machine, a rotatable tool, a 75 shaft therefor, a main drive-shaft, mechanism operatively associated with said main drive-shaft and the tool-shaft whereby the movement of the tool is greater in one direction than in a reverse direction, and means 80 adjustable during the actuation of the main drive-shaft and without interfering with the normal operation thereof for adjusting the extents of movements of the tool, said adjusting means being formed to constantly 85 maintain the relative differential movements of the tool.

8. In a shoe-machine, a rotatable tool, a shaft therefor, a main drive-shaft, mechanism operatively associated with said main 90 drive-shaft and the tool-shaft whereby the rotation of the tool is greater in one direction than in a reverse direction, and means adjustable during the actuation of the main drive-shaft and without interfering with the 95 normal operation thereof for stopping the rotation of the tool.

9. In a shoe-machine, an indenting-tool, means for actuating the same, a work-table operatively associated therewith, and means 100 operating in sequence for controlling the actuation of the tool and shifting the table, in combination with a drive-shaft operable continuously irrespective of said controlling and shifting means.

10. In a shoe-machine, an indenting-tool, means for actuating the same, a work-table operatively associated therewith, and means operating in sequence to first control the actuation of the tool and to subsequently shift 110 the table.

11. In a shoe-machine, an indenting-tool, a shaft for said tool, a main drive-shaft, connections between the main drive-shaft and the tool-shaft, and means whereby the actuation of the tool may be varied during the movement of the main drive-shaft and without interfering with the normal actuation of 115 said main drive-shaft, said means including a pawl and ratchet and a cam for adjusting the extent of movement of said pawl.

12. In a shoe-machine, an indenting-tool, a shaft for said tool, a main drive-shaft, connections between the main drive-shaft and the tool-shaft, and adjustable means whereby the extent of movement of the tool in one direction is greater than in a reverse direction and for varying the movements of the tool during the movement of the main drive-shaft 125 and without interfering with the normal ac- 130

tuation of said main drive-shaft, said means including a series of pawls and ratchets, and cams for adjusting the extents of movements of the pawls.

5 13. In a shoe-machine, an indenting-tool, a shaft for said tool, a main drive-shaft, connections between the main drive-shaft and the tool-shaft, and means whereby the actuation of the tool may be stopped during the movement of the main drive-shaft and without interfering with the normal actuation of the said main drive-shaft, said means including a pawl and ratchet and a cam for throwing the pawl out of engagement with the ratchet.

14. In a shoe-machine, an indenting-tool, a shaft for said tool, a main drive-shaft, connections between the main drive-shaft and the tool-shaft, and adjustable means whereby the extent of movement of the tool in one direction is greater than in a reverse direction and for stopping the movement of the tool during the movement of the main drive-shaft and without interfering with the normal actuation of said main drive-shaft, said means including a series of pawls and ratchets, and cams for throwing the pawls out of engagement with the ratchets.

15. In a shoe-machine, an indenting-tool, a shaft for said tool, a main drive-shaft, connections between the main drive-shaft and the tool-shaft, and means whereby the actuation of the tool may be gradually lessened and finally stopped during the movement of the main drive-shaft and without interfering with the normal actuation of the said main drive-shaft, in combination with a table operatively associated with the indenting-tool, and a single device for shifting the table relative to the tool and for actuating said means.

16. In a shoe-machine, an indenting-tool, a shaft for said tool, a main drive-shaft, connections between the main drive-shaft and the tool-shaft, and means whereby the actuation of the tool may be gradually lessened and finally stopped during the movement of the main drive-shaft and without interfering with the normal actuation of the said main drive-shaft, in combination with a table operatively associated with the indenting-tool, and a single device for shifting the table relative to the tool and for actuating said means, including connections between said means and said table whereby their actuation is in sequence.

17. In a shoe-machine, an indenting-tool, a shaft for said tool, a main drive-shaft, connections between the main drive-shaft and the tool-shaft, and means whereby the actuation of the tool may be gradually lessened and finally stopped during the movement of the main drive-shaft and without interfering with the normal actuation of said main drive-shaft, said means including a pawl and

ratchet and a cam for gradually lessening the extent of actuation of the pawl on the ratchet and finally withdrawing the pawl from engagement with the ratchet.

18. In a shoe-machine, an indenting-tool, a shaft for said tool, a main drive-shaft, connections between the main drive-shaft and the tool-shaft, and means whereby the actuation of the tool may be gradually lessened and finally stopped during the movement of the main drive-shaft and without interfering with the normal actuation of said main drive-shaft, said means including a pawl and ratchet and a cam for gradually lessening the extent of actuation of the pawl on the ratchet and finally withdrawing the pawl from engagement with the ratchet, in combination with a table operatively associated with the indenting-tool, and a single device for shifting the table relative to the tool and for actuating said means.

19. In a shoe-machine, a tool, a table operatively associated therewith, and instrumentalities for successively regulating the actuation of the tool and the shifting of the table including a plurality of operating-rods, a treadle operatively associated with said rods, and means for permitting a relative freedom of movement between one of said rods and said treadle.

20. In a shoe-machine, an indenting-wheel, a rotatable shaft fixed to said wheel, and driving mechanism for said wheel-shaft including a ratchet-wheel secured thereto, an oscillatory pawl-carrier on said shaft, oppositely-disposed pawls on said carrier arranged to engage the ratchet-wheel, and means for oscillating said carrier.

21. In a shoe-machine, an indenting-wheel, a rotatable shaft fixed to said wheel, and driving mechanism for said wheel-shaft including a ratchet-wheel secured thereto, an oscillatory pawl-carrier on said shaft, oppositely-disposed pawls on said carrier arranged to engage the ratchet-wheel, a spring connecting the pawls adapted to draw them toward each other and into engagement with said ratchet-wheel, and means for oscillating said carrier.

22. In a shoe-machine, an indenting-wheel, a rotatable shaft fixed to said wheel, and driving mechanism for said wheel-shaft including a ratchet-wheel secured thereto, an oscillatory pawl-carrier on said shaft, oppositely-disposed spring-actuated pawls on said carrier arranged to engage the ratchet-wheel, and means for oscillating said carrier, in combination with means for throwing the pawls out of engagement with the ratchet-wheel whereby the actuation of the wheel-shaft will stop while permitting the driving mechanism to continue its movement.

23. In a shoe-machine, an indenting-wheel, a rotatable shaft fixed to said wheel, and driving mechanism for said wheel-shaft in-

cluding a ratchet-wheel secured thereto, an oscillatory pawl-carrier on said shaft, oppositely-disposed spring-actuated pawls on said carrier arranged to engage the ratchet-wheel, and means for oscillating said carrier, in combination with means for throwing the pawls out of engagement with the ratchet-wheel whereby the actuation of the wheel-shaft will stop while permitting the driving mechanism to continue its movement, a braking-surface carried by the wheel-shaft, a brake arranged to abut there against to facilitate the stoppage of the wheel-shaft and the wheel when disconnected from the driving mechanism.

24. In a shoe-machine, an indenting-wheel, a rotatable shaft fixed to said wheel, and driving mechanism for said wheel-shaft including a ratchet-wheel secured thereto, an oscillatory pawl-carrier on said shaft, oppositely-disposed spring-actuated pawls on said carrier arranged to engage the ratchet-wheel, and means for oscillating said carrier, in combination with means for throwing the pawls

out of engagement with the ratchet-wheel 25 whereby the actuation of the wheel - shaft will stop while permitting the driving mechanism to continue its movement, a braking-surface carried by the wheel-shaft, a brake arranged to abut there against to facilitate 30 the stoppage of the wheel - shaft and the wheel when disconnected from the driving mechanism, and means for maintaining the brake in constant engagement with the braking-surface on the wheel-shaft whereby to 35 create a retarding influence on the wheel-shaft and wheel while actuated by the driving mechanism.

In testimony whereof we affix our signatures in presence of two witnesses.
